BURGLAR ALARM

Oliver L. Schriner, Attica, N. Y.

Application July 3, 1941, Serial No. 401,030

1 Claim. (Cl. 200—52)

This invention relates to a burglar alarm and has for an object to provide essentially a circuit closer formed of nested metal pipes insulated from each other and adapted to close a circuit to electrically operated alarm devices when an attempt is made to saw through the pipes, the pipes being adapted to form a closure for openings to be protected as well as to form an inclosure for localities to be protected.

A further object is to provide a burglar alarm of this character which will be operated by direct current in the event of failure of the normal alternating current due to tampering or some other causes.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts herein-after fully described and claimed, it being understood that various modifications may be resorted to within the scope of the appended claim without departing from the spirit or sacrificing any of the advantages of the invention.

In the accompanying drawing forming a part of this specification:

Figure 1 is a fragmentary front elevation with parts in section, showing a burglar alarm circuit closer constructed in accordance with the invention and showing the electrical connections thereof with alarm devices.

Figure 2 is a detail longitudinal sectional view showing an intermediate insulator between the inner and the outer pipes.

Figure 3 is a detail sectional view illustrating the manner in which one of the insulated conductors is electrically connected to the inner pipes of the bars.

Referring now to the drawing in which like characters of reference designate similar parts in the various views, the burglar alarm circuit closer comprises bars 10 each formed of an outer pipe 11 and an inner pipe 12 arranged co-axially with each other and spaced from each other at all points. The outer pipe has its ends extended through and welded to a hollow metal frame including upper and lower bars 13 and 14, and end bars 15, one of which is shown. The bars of the frame constitute a ground as well as a mounting to dispose the bars 10 to form a closure for an opening to be protected, or to form an inclosure for a locality to be protected.

The inner pipes 12 are supported in spaced relation to the outer pipes by lower, upper, and in some cases intermediate insulators 16, 17 and 18 respectively. The lower insulator is supported within the lower end of the outer pipe by a metal cap 19 which is screwed on to said end of the pipe and then welded to the bottom metal bar 14. The upper end of this insulator is reduced as shown at 20 and extends into the lower end of the inner pipe 12.

The upper insulator 17 surrounds the upper end of the inner pipe 12 and extends into the upper end of the outer pipe 11. It is secured in place by a flange 21 which overlaps the upper end of the outer pipe 11. The intermediate insulator 18, when used, is of annular form and surrounds the inner pipe as well as contacts with the inner surface of the outer pipe. The intermediate insulator is held in place by screws 22 which are threadedly engaged in the inner pipe above and below the insulator and have their heads engaging with the top and the bottom of the insulator, see Figure 2. The pipes 10 and 11 form terminals of a circuit closer when a surreptitious attempt is made to saw through the pipes, the hack saw forming bridging contact between the terminals during the sawing operation.

The bars 10 are wired for both direct and alternating current and for this purpose a circuit wire 23 is trained through the frame formed by the hollow bars 13 and is bared of insulation at spaced points and welded, or otherwise electrically connected, to the projecting upper ends of the inner pipes 12, as shown in Figure 3. The wire is connected to a signal wire 24 which is connected to one terminal of an alarm device such as an electric bell 25. The other terminal of the alarm device is connected by a signal wire 26 and armature 35 to one terminal of the secondary coil 27 of a step down transformer, the primary coil 28 of which is connected to supply wires 29 from an alternating source of current.

When the outer pipe 10 is sawed through and the hack saw touches the inner pipe the alarm circuit will be closed, and may be traced from the secondary coil 27 of the transformer through the alarm device 25, to the signal wire 24, thence to the conductor wire 23 through the inner pipe 12 to the outer pipe 11 and to the hollow bar 14 which is grounded as shown at 31.

Should the alternating source of supply fail, it is desirable that storage battery current be used to operate the burglar alarm when a surreptitious attempt is made to cut through the bars 10.

For this purpose a storage battery 32 is connected by conductor wire 33 to one terminal 34 of a switch of which this spring retracted armature 35 forms a part. The other terminal 34a of the switch is connected by a wire 36 to one terminal of the electric bell 25a. It will be pointed out that when the alternating source of supply is in operation the step down transformer functions as a relay which coats with the armature 35 to hold the direct current line, which is traced, open at the terminals 34 and 34a but when the alternating source of supply fails the transformer becomes dead and the controlling spring of the armature 35 closes the direct current line at the terminals 34 and 34a.

To complete the directed alarm circuit a signal wire 37 is connected to the other terminal of the alarm device 25a and is connected to a circuit wire 38 which is trained through the frame formed by the hollow bars 14, 15 and 13 and is connected at intervals to conductor wires 39 which pass through the bottom insulators 16 and are trained axially upward in the inner pipes 12. The upper end of each wire 39 is secured in place by an insulator 40 which snugly fits within the inner pipe 12. When the alternating source of current fails the direct current circuit is closed by the circuit closure formed by the inner pipe and the axial wire 39 after both pipes have been sawed through. The direct current circuit may be traced from the batteries 32 to the wire 33, armature 35, wire 36, alarm device 25a, wire 37, wire 38, axial wire 39, and grounded outer pipe 11.

From the above description it is thought that

the construction and operation of the invention will be fully understood without further explanation.

What is claimed is:

- 5 A circuit closer comprising bars each formed of inner and outer metal pipes arranged in coaxial and spaced relation, a hollow metal frame having upper end lower sides in which the bars are mounted, the ends of the outer pipes extending through and welded to said sides of the frame to electrically connect the outer pipes thereto, the lower ends of the inner pipes terminating short of the corresponding ends of the outer pipes and the upper ends of the inner pipes extending above the corresponding ends of the outer pipes, lower and upper insulators spacing the inner pipes from the outer pipes, metal caps supporting the lower insulators within the outer pipes, the caps being screw threaded on the lower ends of the outer pipes and welded to the lower side of the frame, the upper ends of the lower insulators being reduced and extending into the lower ends of the inner pipes, the upper insulators extending into the upper ends of the outer pipes in surrounding relation to the upper ends of the inner pipes,
- 10 20 an insulated conductor housed within the frame and electrically connected to the extended upper ends of the inner pipes, a second insulated conductor housed within the frame, and conductors located axially within the inner pipes and extending through said lower insulators, said conductors having their lower ends connected electrically to said second conductor and having their upper ends insulated from the inner pipes.
